US00D357484S

United States Patent [19]

Montague et al.

[11] Patent Number: Des. 357,484

[45] Date of Patent: ** Apr. 18, 1995

[54] INJECTION MOLDING MACHINE

[75] Inventors: **Edgar B. Montague; Mark D. Gildersleeve**, both of Charlotte, N.C.
[73] Assignee: **Cincinnati Milacron Inc.**, Cincinnati, Ohio
[**] Term: **14 Years**
[21] Appl. No.: **16,325**
[22] Filed: **Dec. 13, 1993**
[52] U.S. Cl. **D15/135**
[58] Field of Search ..... **D15/135; 425/146, 171, 425/181, 218, 436 R M, 556, 547**

[57] CLAIM

The ornamental design for an injection molding machine, as shown.

DESCRIPTION

FIG. 1 is a front perspective view of an injection molding machine showing our new design;
FIG. 2 is a front elevational view thereof;
FIG. 3 is a right side elevational view thereof;
FIG. 4 is a left side elevational view thereof;
FIG. 5 is a rear elevational view thereof; and,
FIG. 6 is a top plan view thereof.

FIG. 1

FIG. 2

FIG. 4

FIG. 3

FIG. 5

FIG. 6
